[57] CLAIM

The ornamental design for a sole for a marching shoe, as shown and described.

DESCRIPTION

FIG. 1 is a perspective view of a sole for a marching shoe embodying my new design; The broken lines showing a shoe upper being for illustrative purposes only and forming no part of the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
